UNITED STATES PATENT OFFICE.

ORLANDO A. LEE, OF MANSFIELD, OHIO.

WRENCH.

SPECIFICATION forming part of Letters Patent No. 294,642, dated March 4, 1884.

Application filed January 10, 1884. (No model.)

To all whom it may concern:

Be it known that I, ORLANDO A. LEE, a citizen of the United States of America, residing at Mansfield, in the county of Richland and State of Ohio, have invented certain new and useful Improvements in Wrenches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain new and useful improvements in sliding-jaw wrenches, the object of my improvement being to provide a cheap and effective means for adjusting the sliding jaw against the stationary jaw and upon a nut or other object.

My invention consists in the construction and combination of the parts, as will be specifically pointed out in the claims.

In the accompanying drawings, which illustrate my invention, Figure 1 is a side view; Fig. 2, a vertical section. Fig. 3 is a transverse section taken through the line $x-x$ of Fig. 1; and Fig. 4 is a detailed view of the adjustable jaw, partly in section.

Referring to the drawings, A represents the stationary jaw of a nut-wrench, which is constructed in the usual manner, and is provided on one side of the shank A' with a flat face, a, and on the opposite side with a concave trans-

versely-serrated face, a'. At a suitable point at a distance less than the length of the adjustable jaw the shank A' is provided with inclined serrations B B, which may, if desirable, form a portion of a screw-thread. At a point on

the shank A' where these serrations stop the shank is reduced in diameter, and passes through a handle and a collar. The lower end of the shank is rounded and screw-threaded for the reception of a retaining-collar, which

also performs the function of a nut, the collar and nut being formed in one piece. The shank A', at the point below the stationary jaw and the collar secured to the upper part of the handle, is substantially rectangular in cross-section, as shown in Fig. 3. Preferably the outer edges are curved or rounded, as shown at b. The sliding jaw C is provided with a

longitudinal opening, c, which corresponds in cross-section with the shape of the shank, and the shank passes through this opening, so that the movable jaw will slide freely thereon. This opening c is slightly larger than the shank, and by forming the shank and this opening with two flat sides the jaw is prevented from turning thereon. One of the faces of the sliding jaw is flat and the other one curved, as shown at c', and this curved portion of the jaw is recessed for the reception of the serrated plate, which is secured thereto by means of a transverse screw. Thus the wrench may be used for grasping round objects as well as those having angular sides. The jaw C is cut away at its lower portion, or that part adjacent to the handle, so as to provide an opening, in which is secured a thumb or adjusting piece, D, and the opening C' in the lower portion of the jaw extends across the same, so as to leave vertical walls or connecting portions d. The thumb-piece D is provided with an oval opening, E, which has the sides opposite the less diameter of the same provided with inclined serrations and recesses, which will engage with the serrated portions of the shank. Above the thumb-piece D the adjustable jaw is provided with a perforation, within which is secured a spring-bolt, F, which will bear against one side of the thumb-piece, and will force it away from the upper portion of the opening in which the thumb-piece operates, and will also prevent rattling of this loosely-working part of the wrench.

Having thus described the construction of my invention, which is fully shown in the accompanying drawings, I will now proceed to describe its operation.

The parts being organized as shown in Figs. 1 and 2 of the drawings, when it is desirable to adjust the jaws to any particular size the thumb-piece D, which projects beyond the adjustable jaw, is turned so that said thumb-piece will be nearly at right angles with the sides of the sliding jaw, thus bringing the opening in said thumb-piece in such a position that the jaw will slide easily upon the shank, the recessed or serrated edges on the interior of the opening in this thumb-piece being out of engagement with the serrations on the shank, and when in this position the jaw can be moved either backward or forward; and when placed

over a nut or other object the thumb-piece is turned back to the position shown in Fig. 1, this movement causing the inclined serrations to engage with each other, and these serrations, being inclined, as heretofore stated, will carry the jaw slightly forward, so as to clamp the same upon the nut. The spring-bolt F, hereinbefore referred to, will exert a pressure upon the thumb-piece, and will prevent the same from turning when a pressure is not upon the jaws.

Having thus described my invention, what I claim as new, and desire to secure by Letters Patent, is—

15. 1. A wrench provided with a stationary jaw and a shank with inclined serrations $b' b'$ and smooth sides, in combination with an adjustable jaw recessed for the reception of a thumb-piece, said thumb-piece having an oval-shaped opening, the sides of said opening be-

ing provided with serrations $b b$, and a spring-actuated sliding bolt bearing upon the thumb-piece, the parts being organized substantially as shown, and for the purpose set forth.

2. In a wrench having a stationary and sliding jaw, the shank B, screw-threaded on opposite sides, and provided with intermediate plain surfaces, and the thumb-piece D, located upon the shank and embraced by the sliding jaw, so that the thumb-piece will extend beyond the same on opposite sides, the parts being organized and combined substantially as shown, and for the purpose set forth.

In testimony whereof I affix my signature in presence of two witnesses.

ORLANDO A. LEE.
